(57) **CLAIM**

The ornamental design for a control unit to monitor and control valve, as shown and described.

DESCRIPTION

The patent or application file contains at least one drawing executed in color. Copies of this patent or patent application publication with color drawing(s) will be provided by the Office upon request and payment of the necessary fee.

1.-3. Control unit to monitor and control valve

Fig. 1.1 is a front, right perspective view of a control unit to monitor and control valve showing our new design; fig. 1.2 is a top plan view thereof; fig. 1.3 is a front elevational view thereof; fig. 1.4 is a right side elevational view thereof; fig. 1.5 is a left side elevational view thereof; fig. 1.6 is a rear elevational view thereof; fig. 1.7 is a bottom plan view thereof.

The broken lines shown in reproductions 1.1, 1.3-1.4, 1.6 and 1.7 depict unclaimed portions of the control unit only and form no part of the claimed design. The grayed-out regions within the broken line boundaries shown in repro-

(Continued)

ductions 2.1, 2.3, 2.4, 2.7, 3.1, 3.3, 3.4 and 3.7 depict unclaimed portions of the control unit only and form no part of the claimed design.
